Attorney

UNITED STATES PATENT OFFICE.

ELMER ENNIS, OF ARAPAHO, OKLAHOMA.

DUMPING-RECEPACLE.

1,287,929.

Specification of Letters Patent. Patented Dec. 17, 1918.

Original application filed May 25, 1918, Serial No. 236,606. Divided and this application filed July 24, 1918. Serial No. 246,578.

To all whom it may concern:

Be it known that I, ELMER ENNIS, a citizen of the United States, residing at Arapaho, in the county of Custer and State of Oklahoma, have invented certain new and useful Improvements in Dumping-Receptacles, of which the following is a specification, reference being had to the accompanying drawings.

10 This invention relates to certain improvements in dumping receptacles, and it is an object of the invention to provide a receptacle of this general character having novel and improved means whereby the contents 15 of said receptacle may be readily dumped therefrom under the influence of the weight of the load.

The invention consists in the details of construction and in the combination and 20 arrangement of the several parts of my improved hoisting receptacle whereby certain important advantages are attained and the device rendered simpler, less expensive and otherwise more convenient and advantageous 25 for use, as will be hereinafter more fully set forth.

The novel features of my invention will hereinafter be definitely claimed.

In order that my invention may be the 30 better understood, I will now proceed to describe the same with reference to the accompanying drawings, wherein:

Figure 1 is a view in elevation of a dumping receptacle constructed in accordance 35 with an embodiment of my invention;

Fig. 2 is a view in bottom plan of the dumping receptacle as herein embodied;

Fig. 3 is a fragmentary view partly in side elevation and partly in section illustrating the locking means for the swinging bottom panels as comprised in the receptacle structure; and

Fig. 4 is a fragmentary view in elevation of the cam member and the operating lever 45 therefor as included in the locking mechanism carried by the receptacle.

As disclosed in the accompanying drawings R denotes a receptacle which may be constructed in any desired manner and be 50 of any preferred capacity but as herein disclosed the bottom of the receptacle comprises two swinging sections 43 hingedly connected at their outer longitudinal margins with the rod 44 supported by the depending bearings 45 carried by the sides of

the receptacle R. When the sections 43 are at the limit of their swinging movement toward the receptacle R the bottom of such receptacle is substantially closed.

The corner portions of the receptacle R 60 are provided with the upstanding ears or brackets 17. Engaged with the upstanding ears or brackets 17 are the extremities of the yokes 16. The central portions of the yokes 16 are engageable with the hook members 15 included in the hanger H and which hanger is adapted to coact with a fall block or the like in a conventional manner, and preferably in connection with an apparatus as particularly set forth in my co-pending 70 application Serial No. 236,606, filed May 25, 1918 and of which the present application is a division.

The opposite ends of each of the sections 43 adjacent the free longitudinal margin 75 thereof are provided with the outwardly directed extensions 46 and coacting with each of said extensions 46 is a holding dog or latch 47 pivotally engaged with the end wall of the receptacle R. Each end of the 80 receptacle R is provided with a pair of holding dogs or latches 47 and rotatably supported by the end of the receptacle R and between said latches or dogs 47 below their pivots 48 is a cam member 49. Upon 85 rotation of the cam member 49 in one direction it will be at once understood that the latches or dogs 47 will be caused to move in unison but in reverse directions so that the latches or dogs will be disengaged 90 from the extensions 46 so that the sections 43 may drop so that the load carried by the receptacle R may be readily dumped or discharged therefrom.

Each of the cams 49 is provided with an 95 upstanding lever 50. Operatively engaged with the upper end portion of each of the levers 50 is a pitman 51 which is also operatively engaged with a rock arm 52 carried by an end portion of the shaft 53 supported 100 by a side of the receptacle R and extending in a direction longitudinally of each of the bottom sections 43.

The rock arms 52 are reversely directed as particularly illustrated in Fig. 1 so 105 that one of the members 52 is extended and affords an operating handle 54 and this lever is disposed through the guide 55 so that the lever is held against lateral movement when strain is imposed upon the handle 54 110

to release the dogs or latches 47 from the extensions 46. The lower portion of this lever 50 has secured thereto a retractile member 56 which is also suitably anchored to the 5 adjacent end or wall of the receptacle R. The member 56 serves to normally maintain the levers 50 in a vertical position and the cams in a position whereby no obstruction is offered to the engagement of the latches or dogs 47 with the extensions 46.

Each pair of latches or holding dogs 47 above their pivots 48 are connected by an 10 expandible member 57 which serves to constantly urge the lower or working ends of 15 the latches or dogs 47 inwardly so that the desired engagement of the latches or dogs 47 with the extensions 46 is assured.

From the foregoing description, it is 20 thought to be obvious that a dumping receptacle constructed in accordance with my invention is particularly well adapted for use by reason of the convenience and facility 25 with which it may be assembled and operated and it will also be obvious that my invention is susceptible of some change and modification without departing from the principles and spirit thereof and for this reason I do not wish to be understood as 30 limiting myself to the precise arrangement and formation of the several parts herein shown in carrying out my invention in practice except as hereinafter claimed.

I claim:

1. A receptacle, swinging bottom sections 35 therefor, said sections being provided with extensions arranged in close proximity when the sections are in closed position, a pair of vertically disposed holding dogs pivotally engaged substantially midway their lengths 40 with the side wall of the receptacle for engagement with the extensions to hold the bottom sections in closed position, and a cam member interposed between the holding dogs below their pivots and having sliding contact 45 with the opposed faces of the dogs for imparting movement thereto in unison but

in reverse directions to disengage the dogs from the extensions.

2. A receptacle, swinging bottom sections therefor, said sections being provided with 50 extensions arranged in close proximity when the sections are in closed position, a pair of holding dogs pivotally engaged substantially midway their lengths with a side wall of the receptacle for engagement with the extensions to hold the bottom sections in closed position, a cam member interposed between the holding dogs below their pivots and having sliding contact 55 with the opposed faces of the dogs for imparting movement thereto in unison but in reverse directions to disengage the dogs from the extensions, and means coacting with the upper end portions of the dogs for constantly urging the same in working position.

3. A receptacle, swinging bottom sections carried by the receptacle, said sections being provided with extensions extending beneath opposite sides of the receptacle, a pair of swinging holding dogs carried by each of the 70 walls of the receptacle adjacent the extension, and engageable with said extensions for holding the sections in closed position, a cam member interposed between the dogs of each pair for moving the same in unison but in 75 reverse directions, a rock shaft carried by a third wall of the receptacle and provided at its opposite ends with reversely directed rock arms, upstanding levers carried by the cam members, pitmen connecting said levers and 80 the rock arms whereby both of the cams are caused to rotate in unison to move the holding dogs simultaneously but in reverse directions, one of said levers being provided with an extension to afford an operating handle. 85

In testimony whereof I hereunto affix my signature in the presence of two witnesses:

ELMER ENNIS.

Witnesses:

Mrs. M. O. DAWSON,
WELTHA OWEN.
